Des. 194,622
Patented Feb. 19, 1963

194,622

PITCHER

James B. Swett, 8 Devonshire Drive, Barrington, R.I.

Filed Nov. 20, 1961, Ser. No. 67,664

Term of patent 14 years

(Cl. D44—21)

FIG. 1

FIG. 4

FIG. 2

FIG. 3

I claim:

The ornamental design for a pitcher, as shown.
